INVENTOR:

by Thomas Morse
Mr. Wallace White ATTY.

UNITED STATES PATENT OFFICE.

THOMAS MORSE, OF BEXLEY, NEAR SYDNEY, NEW SOUTH WALES, AUSTRALIA.

LUGGAGE-CARRIER.

1,312,562.

Specification of Letters Patent.

Patented Aug. 12, 1919.

Application filed July 11, 1918. Serial No. 244,432.

To all whom it may concern:

Be it known that I, THOMAS MORSE, a subject of the King of Great Britain, residing at "Esrom" Harrow Road, Bexley, 5 near Sydney, in the State of New South Wales and Commonwealth of Australia, engineer, have invented a new and useful Luggage-Carrier, of which the following is a specification.

10 This invention relates to devices for retaining suit cases, kit bags, packages, parcels and the like upon the foot boards of automobiles, upon boards or platforms or shelving of other vehicles or upon stationary shelving. And it has been specially devised in order to provide a package retainer 15 for holding baggage on automobiles which is adjustable to grip or seize the article or articles retained therein and which is readily positioned is light in weight, simple in construction, cheap to manufacture, and at the same time is removable and foldable when not in use.

20 This improved package retainer especially useful for holding baggage on automobiles has a horizontal channeled base member adapted to be attached transversely of the footboard or shelf, a sliding racked member in said base, a pawl or catch to hold 25 said racked member in set position a removable vertical inner member having a grip or tongue adapted to fit into one of a series of slots in a raised portion or in a side extension of the base at or near the 30 inner end of said base and a vertical outer member connected to the outer end of the rack member preferably by means of a jack-knife joint.

35 But in order that this invention may be readily carried into effect a practical application thereof will now be described with reference to the drawings accompanying and forming part of this complete specification in which:—

40 Figure 1 is a perspective view of two improved step retainers applied to the footboard of an automobile and holding two dotted line packages the left hand one shown as secured thereto by screws or the like and 45 the right hand one as held thereon by clips.

50 Fig. 2 is a side sectional elevation of a package retainer.

55 Figs. 3 and 4 are transverse and longitudinal sectional part elevations respectively showing the grip or tongue of the inner vertical member in place in the base. Figs. 5

and 6 are front elevation and transverse sectional part elevation respectively showing a spring pawl or catch for the sliding racked member. Fig. 7 is a longitudinal 60 sectional part elevation showing a jack-knife joint for outer vertical member. Fig. 8 is a sectional part plan showing a modified construction of the sliding member and pawl therefor and Figs. 9 and 10 are part 65 plan and transverse sectional part elevation respectively of a modified construction of channeled base. Fig. 11 is a detail view showing one form of attaching clip for the base.

70 The channel 12 has a flat base plate 13 with flanges 14 having holes 15 for screws whereby it may be secured to a footboard 16 or to shelving. Within the channel 12 is a slidable member 17 having a rack 18 adapted to be engaged by a spring pawl 19 having stem 20 with cross head 21 in which is a notch or finger hold 22. About said stem 20 and between it and the casing 23 is an expanding spring 24 adapted to press 80 the pawl 19 into engagement with the rack 18. The casing 23 is carried on a turn-over portion 25 of the base plate 13. The outer end of slidable member 17 has ears 26 between which fits the knuckle 27 of foldable 85 member 28 and through both of which is pivot pin 29 on which said member may hinge as far as stop 30 will allow. The channel 12 has a top or cover plate 31 in which are a plurality of slots 32 each of 90 which is adapted to receive the hook grip 33 on the lower end of removable member 34 and hold said member vertical. Vertical members 28 and 34 preferably have each a chape or eye 35 at top adapted to receive 95 straps or cords preferably extending from one to the other to hold packages or luggage between them more securely.

100 In a modified construction the flanges 14 on each side of channel 12 have recesses 36 to allow said flanges 14 to slide under clips 37 secured to footboard 16 until said clips are engaged by a spring catch 38 or the like device on the flanges 14 and so releasably secure the channel 12 to 105 the footboard 16. Further the member 17 may be modified by having the rack 18 upon its side in which case said rack is adapted to be engaged by pawl 39 having spring 40 which has a casing 41 on channel 12. Further the channel 12 may have an enlargement 42 longitudinally, (Figs. 9 110.

and 10) to provide the slots 32 for the vertical member.

Upon the footboard of an automobile or elsewhere on a vehicle this improved retainer would be in pairs or sets a suitable distance apart and when not in use the outer vertical member 28 may be removed or be folded downwardly and inwardly while the inner vertical member 34 would be removed and placed handily. In use the parts being brought together and erected the slideable member 17 is drawn out the bags or the like are packed in position after which said member 17 is thrust inwardly so as to seize or grip the packages or luggage and support them between the vertical members 28 and 34. If desirable, straps may then be inserted into the eyes 35 of the members 28 and 34 to secure the luggage against vertical movement.

Upon shelving this improved retainer could be arranged at intervals and in series and one or a series could be adjusted as desired.

When employing two channel members such as the right hand channel member shown in Fig. 1, the members are slid beneath the clips 37 so that the clips prevent upward movement of the member by virtue of the flanges 14, at the same time the spring catch 38 engages one of the innermost clips 37. In this position, outward longitudinal movement of the channel member is prevented by virtue of the spring clip, while inward longitudinal movement thereof is prevented by means of the overturned portion 25 which now engages the outer edge of the support 16, thus the channel member is securely locked against longitudinal movement in either direction. However, it will be obvious that the channel member may be readily removed by disengaging the catch 38 from the clip 37 and withdrawing the channel member from beneath the clips. It has been found in practice that this form of the invention is highly practicable as the channel member may be entirely removed when not in use.

What I claim as my invention and desire to secure by Letters Patent is:—

1. An improved package retainer comprising a channeled member having a top or cover plate thereon formed with a series of slots and adapted to be secured to a support, a racked member slideable within said channeled member, a spring pawl adapted to engage and hold said racked member in set position, an outer vertical member

hingedly connected to said racked member, and an inner vertical member having a grip hook on its lower end adapted to position in one of the slots in said top or cover plate substantially as herein described and explained.

2. A package retainer comprising in combination with a support, a channel member secured to said support and having slots formed therein, a vertical member on the channel member, a hook on one end of said vertical member and engageable in any of said slots for supporting said member in vertical position, a bar slideable in the channel member, means on said bar and coacting means on one end of the channel member for locking the bar in horizontal adjusted position, and a second vertical member hinged to said bar.

3. A package retainer comprising in combination with a support, clips secured to the support, a channel member, flanges formed on said member and engageable with said clips for retaining the member on the support, means carried by said member and engageable with said clips for locking said member against longitudinal displacement in one direction, and vertical members adjustable on said channel member.

4. A package retainer as embodied in claim 3, and an angular extension formed on the channel member and engageable with one edge of the support, said extension coacting with said means to prevent longitudinal displacement of the channel member in either direction.

5. A package retainer comprising in combination with a support, a channel member having a sliding connection with said support, an angular extension formed on one end of the member and engageable with the edge of the support for limiting the movement of the member in one direction, a toothed bar slideable within said member, a vertical member having a folding connection with said bar, a second vertical member adjustable on said channel member, and a spring pressed latch carried by said extension and engageable with the teeth on said bar for locking the latter in adjusted position.

In testimony whereof I have signed my name to this specification in the presence of two subscribing witnesses.

THOMAS MORSE.
